UNITED STATES PATENT OFFICE.

JOHN M. SCHULTZ, OF CHICAGO, ILLINOIS, ASSIGNOR, BY DIRECT AND MESNE ASSIGNMENTS, TO JOHN S. CHENNEOUR, OF CHICAGO, ILLINOIS.

TYPEWRITER ATTACHMENT.

1,423,687.

Specification of Letters Patent. Patented July 25, 1922.

Application filed July 9, 1919. Serial No. 309,708.

To all whom it may concern:

Be it known that I, JOHN M. SCHULTZ, a citizen of the United States, residing at Chicago, in the county of Cook and State of

5 Illinois, have invented certain new and useful Improvements in a Typewriter Attachment, of which the following is a description.

My invention belongs to that general class 10 of devices known as typewriter attachments, and relates particularly to an attachment to be placed on the shift key bar of typewriters to lock the bar in a position whereby the machine will write caps. The same is shown 15 as applicable for use on Underwood typewriters to replace a small lever used on the old types of machines, thereby making the machine up to date so that a locking key may be depressed to shift and lock the 20 machine and cause the writing of capitals, and the shift lever key on the opposite side of the machine upon being depressed will automatically release the device. The invention has among its objects the production of a 25 device of the kind described that is simple, convenient, durable, efficient and satisfactory for use wherever found applicable. Many other objects and advantages of the construction herein shown and described 30 will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

40 Fig. 1 is a view illustrating the application of the device to an Underwood machine, a portion of the machine being shown;

Fig. 2 is a plan view of the two shift keys with my device applied to one of the bars 45 thereof;

Fig. 3 is a side elevation of my device, a portion of one of the shift bars, together with the locking member;

Fig. 4 is a similar view showing the device 50 in operation;

Fig. 5 is a plan view of the same;

Fig. 6 is a sectional view taken substantially on line 6—6 of Fig. 3;

Fig. 7 is a perspective view of my attachment, the spring and fastening means not shown;

Fig. 8 is a plan view of the shift lever at the opposite side of the machine;

Fig. 9 is a side elevation of the same looking on line 9—9 of Figure 8;

Fig. 10 is a perspective view showing the two shift levers or bars with my device attached thereto; and

Fig. 11 is a sectional view taken substantially on line 11—11 of Fig. 9.

Referring to the drawings, 1 represents one of the shift levers provided with an operating key 2, and 3 the other lever provided with an operating key 4, it being understood that as either one of the keys are 70 depressed, the platen is raised or the machine so controlled that capitals will be struck in place of small letters. In the older machines, for example the old type of Underwood machines serially numbered less 75 than eight hundred thousand, a lever is provided for locking the shifting mechanism to print capitals, but frequently, and in fact in many cases, the purpose of this lever is not understood, and when so understood the 80 same is inconvenient to use and is not always accurately set to perform the functions. My device is an attachment to be placed on machines in lieu of the lever herefore used, which attachment will have a 85 locking key, the use of which will be readily understood, which will serve to control the lock latch so that the same may be operated to lock the machine to print capitals and prevent its being unlocked in case of the 90 accidental operation of the shift key adjacent thereto, but which will permit the release of the shifting mechanism upon the operation of the shift key at the opposite side of the machine. In order that the application of the same may be understood, it

95 may be stated that 5 represents a pin or lug on the lever 1, the same arranged to cooperate with the latch or locking member 6 arranged on a rock shaft 7. The latch member 6 is provided with a face 8 arranged to engage with the pin 5 and lock the lever 1 down, the device which I have referred to as an inconvenient lever being adapted to control the latch and permit or prevent its 100 engagement with the pin 5, depending upon the adjustment. The operation of the same, however, may be controlled by rock shaft 7 and arm 10 secured thereto, and a cooper-

105 ating pin 12 on the shift lever arm 3, and 110 this part of the mechanism I do not change.

My attachment consists of a part 15 which

2
may be termed a lock bar or lever, which is provided with a key 16 preferably marked to indicate that it is the shift lock. The same is also formed with a hole 17 so that the same may be secured by a screw bolt 18 or the equivalent to the arm 1, it being necessary, however, in the type of machine referred to, to bore a hole in the lever 1. Member 15 is provided with an upwardly extending part 19 which is formed with a flange 20, having faces 21 and 22. The face 21 is arranged to cooperate with the face 9 and the latch 6, and the face 22 with the upper edge 26 of the latch, as will be more fully understood from the description of the operation of the device. In applying the device, the old attachment is removed from the machine and a hole drilled in the lever 1 for the screw 18, and a hole preferably drilled at 25 for engagement or securing of the spring 23, and the opposite end of each is secured at hole 24 to the lock arm or lever 15.

In Fig. 1 is illustrated one form of mechanism between the platen and shift key. Referring to this figure, the lever 1 is supported at 28, the same being provided with an arm 29 arranged to cooperate with arm 30—31 pivotally secured at 32, the same being operatively connected so as to manipulate the platen 33. Obviously as the shift key at either side of the machine is manipulated, the platen 33 is controlled.

The operation of the device may be briefly described as follows: As the key 2 is depressed, the same shifts the platen to write caps, and at the same time the pin 5 moves down the face 9, but owing to the engagement of face 21 on flange 20 with the face 9, as shown in Fig. 3 by the dotted lines, the latch or lock 6 is maintained out of operation. If it is desired to shift and lock the platen or other mechanism, key 16 is depressed, this not only depressing lever 1, but it raises the flange 20 so that as the pin 5 rides down the edge 9 and is engaged at 8, face 22 of the flange rides over the top 26 of the latch, as indicated in Fig. 4. This locks the latch in place and prevents the same being released by manipulating key 2 or key 16. The pin 5 will be engaged by the latch 6 until key 4 is depressed. When key 4 is depressed, however, pin 12 cooperating with the arm 10, rocks shaft 7 and with it the latch 6, so that pin 5 is disengaged and the shaft arm raised under the pressure of the weight of the mechanism and such other means as may be provided, not considered necessary to describe in detail herein. As is obvious, as soon as the latch 6 is dropped out of engagement, it tends to rock member 15 on its pivotal connection 18, this movement being permitted as the same is only maintained in position by the

spring 23. As soon as the shift arm is released, flange 20 returns to the position substantially as shown in Fig. 3, so that the shift key 2 may be used until such time as key 16 is again depressed, locking the mechanism in the shifted position.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a typewriting machine, a platen shift lever having a pin projecting from one side thereof, a rocking lock lever pivotally mounted on said shift lever having an integral extension projecting at right angles thereto, a finger key connected with said lever, a pivoted latch lever, said right angle extension portion of the lock lever being adapted to normally prevent locking cooperation between said pin and pivoted latch lever, but adapted upon the actuation of said lever to be moved rearwardly from said pin slidably on the upper portion of the latch lever to a position to permit a portion of the latch to ride over and engage said pin, said angle extension of said lock lever directly engaging the upper surface of the latch lever when the same cooperates with the pin to hold the latch lever in locked position.

2. In a typewriting machine, the combination with a platen shift lever having a projection extending therefrom, a locking lever pivotally mounted on said shift lever having an upstanding portion provided with an integral right angle extension, and a cut-out portion arranged at the forward edge of said locking lever, a pivoted latch lever mounted adjacent said pin and having a forwardly extending latch face, said extension on the lock lever being adapted to normally engage said projection, and upon a shifting of the lock lever to move rearwardly from the projection to permit said projection to be engaged by the under side of the latch surface of said latch lever said right angle extension directly engaging with the upper face on the latch lever to retain the same in a latched position.

In testimony whereof, I have hereunto signed my name in the presence of two subscribing witnesses.

JOHN M. SCHULTZ.
